Primary Examiner — Rosemary K Tarcza*(74) Attorney, Agent, or Firm* — Brinks Gilson & Lione**CLAIM**

The ornamental design for a battery portion for a vaporizer, as shown and described.

DESCRIPTION

FIG. 1 is an exploded front perspective view of a battery portion for a vaporizer with a cartomizer removed from the battery portion, the cartomizer illustrated in broken lines; FIG. 2 is a front view of the battery portion of FIG. 1; FIG. 3 is a side view of the battery portion of FIG. 1; FIG. 4 is a rear view of the battery portion of FIG. 1; FIG. 5 is a top view of the battery portion of FIG. 1; and, FIG. 6 is a bottom view of the battery portion of FIG. 1. The broken lines shown in the drawings are included for the purpose of illustrating environmental structure and form no part of the claimed design.
